L. V. LEWIS.

RAILWAY SIGNALING SYSTEM.
APPLICATION FILED JULY 9, 1919.

Patented Dec. 16, 1919.

UNITED STATES PATENT OFFICE.

LLOYD V. LEWIS, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM.

1,324,912.

Specification of Letters Patent. Patented Dec. 16, 1919.

Application filed July 9, 1919. Serial No. 309,712.

To all whom it may concern:

Be it known that I, LLOYD V. LEWIS, a citizen of the United States, residing at Wilkinsburg, in the county of Allegheny and 5 State of Pennsylvania; have invented certain new and useful Improvements in Railway Signaling Systems, of which the following is a specification.

My invention relates to signaling systems 10 for railways, and particularly to systems of the type comprising roadside signals for governing the passage of cars and trains along the railway, and alternating current track circuits for controlling such signals.

One object of my invention is the provision of a novel and useful combination of apparatus whereby the signals may be reliably and effectively controlled by only a 15 minute amount of energy abstracted from the track circuits. The invention readily adapts itself, therefore, to signaling systems 20 for railways the track rails of which are electrically continuous throughout, although it is not limited to signaling on a road of this 25 type.

I will describe one form of signaling system embodying my invention, and will then point out the novel features thereof in 30 claims.

In the accompanying drawings, Figure 1 35 is a view showing diagrammatically one form of signaling system embodying my invention. Fig. 2 is a fragmental view showing an alternative means which may be employed in lieu of the means shown in Fig. 1, for abstracting signal controlling energy 40 from the track circuit.

Similar reference characters refer to similar parts in each of the views.

Referring first to Fig. 1, the reference 45 characters R and R' designate the track rails of a railway over which traffic normally moves in the direction indicated by the arrow. The track rails, in the system shown herein, are electrically continuous throughout. The railway here shown is of the type employing direct current for the propulsion 50 of the cars or trains, and hence it is provided with a trolley wire or third rail T, and with a propulsion generator G^P one terminal of

which is connected with the trolley wire and the other terminal with ground.

The railway is divided into blocks by means of bonds, 2, 2^a, etc., of low impedance connected across the rails, there being two 55 bonds at each junction of adjacent blocks, separated by a short distance such that the impedance of the intervening lengths of rails will prevent the flow of an appreciable amount of alternating track circuit current 60 from block to block. Only one complete block A-B is shown in the drawing, but it is understood that the apparatus shown in this block would be duplicated for a plurality of successive blocks, as indicated by the apparatus illustrated for the ends of the blocks 65 lying to the right and to the left of block A-B.

Located at or near the middle of the block 70 A-B is a transformer U whose secondary is connected across the track rails, and whose primary is connected with a transmission line M to which alternating signaling current is supplied by a generator G^A. This transformer is, then, the source of track circuit current for the block A-B. 75

Located adjacent the bond 2^a is a coil 3^a which is in inductive relation to the bond and to a short length of each rail near the bond, so that alternating current is induced 80 in this coil due to the current in the track circuit. The energy induced in this coil is employed to control a signal controlling relay P^a, which relay comprises a rotor 27 and two stator windings 25 and 26. One winding 26 is constantly supplied with alternating current from the secondary 18 of a transformer L^a, the primary of which is connected across the transmission line M, while the other winding 25 is controlled by the track 85 circuit current induced in coil 3^a. It is obvious, however, that when the track circuit current is of a commercial value, the amount of energy which is created in coil 3^a will be minute, and that consequently this energy, 90 cannot be applied directly to the relay P^a if this relay is of reliable and rugged construction. For this reason, I interpose between the coil 3^a and the winding 25 of relay P^a an amplifier K^a of the electron type, com- 95 100

prising a vacuum bulb containing a filament 4, a plate 5, and a grid 6 located between the two. The filament 4 is constantly heated by alternating current supplied from a secondary 8 of the transformer L^a . One terminal 5 of the coil 3^a is connected with the grid 6 of an amplifier K^a through a condenser 9, whereas the other terminal of the coil 3^a is connected with the filament 4 of this amplifier. As here shown, this latter connection is 10 accomplished by connecting the terminal of the coil with the middle point of the secondary 8 of transformer L^a , which serves to energize filament 4, the purpose of this form of connection being to maintain a constant average potential difference between grid 6 and filament 4 irrespective of the alternating potential difference across the filament. The purpose of the condenser 9 is, of course, to insure 15 that the potential on the grid 6 will always be negative with relation to the potential of filament 4 in order to minimize the flow of electrons from the filament to the grid. This grid circuit for the amplifier, 20 that is, the circuit including coil 3^a, I will term a "trackway circuit."

The amplifier K^a is provided with a plate circuit which includes a source of direct current and winding 25 of the signal controlling relay P^a . As here shown, the direct current source for this circuit is the propulsion generator G^p , and the circuit is from the trolley wire T , through wire 10, winding 25 of relay P^a and condenser 11 in multiple, wire 12, plate 5, filament 4, wires 13 and 14 in multiple, the two halves of secondary 8 in multiple, and wires 15 and 16 to ground at point 17, thence to generator G^d . The local circuit comprising condenser 11 and winding 25 of relay P^a is tuned to 25 resonance at the frequency of the track circuit current. The variations in potential between the filament 4 and the grid 6 will, of course, cause variations of considerably greater magnitude in the current flowing in the plate circuit of the amplifier, and these variations are of sufficient amplitude to reliably control a rugged commercial relay. This relay is, of course, of a type adapted 30 to respond to alternating current and not to direct current. By providing relay P^a with two windings one of which is constantly supplied with energy from transformer L^a , the relay may be operated on about 0.02 watt supplied to winding 25 by 35 amplifier K^a . If this relay were of a single winding type the entire energy to which were supplied by the amplifier K^a , the energy required from this amplifier would be 40 about 2 watts, and this would not be commercially practicable because it would require an excessive track circuit current or an excessive number of turns in coil 3^a.

It follows from the foregoing that when

track circuit current from transformer U 65 flows through the bond 2^a, it will cause relay P^a to be energized, but that when the supply of track circuit current to the bond 2^a is discontinued relay P^a will become deenergized.

70

The right-hand end of block A-B is provided with a coil 3^b, an amplifier K^b , and a relay P^b , these parts being arranged and connected in the same manner as the corresponding parts at the left-hand end of the 75 block.

Located at the entrance end of the block A-B is a signal S^b , which is controlled by both relays P^a and P^b . The circuit for this signal is from secondary 18 of transformer L^a through wires 19 and 19^a, contact 20 of relay P^a , wire 21, contact 22 of relay P^b , wire 23, operating mechanism of signal S^b , and wires 24, 24^a and 24^b to the secondary 80 18 of transformer L^a . It follows, therefore, that signal S^b will indicate "proceed" when both relays P^a and P^b are energized, and "stop" when either or both of these relays are deenergized.

The operation of the system is as follows: 90

When block A-B is unoccupied, energy is induced in the coils 3^a and 3^b by current flowing in the track circuit from transformer U , so that signal S^b indicates proceed. When a train moving in the direction 95 indicated by the arrow enters this block, it shunts the greater part of the current from the bond 2^b and the track rails adjacent this bond, so that relay P^b becomes deenergized, whereupon signal S^b moves to the stop position. As the train approaches the point at which transformer U is connected with the rails, the amount of track circuit current flowing to the left from this point of connection becomes reduced to such value that relay 100 P^a opens. After the train passes some distance beyond the point at which transformer U is connected with the rails, relay P^b again becomes energized, but signal S^b remains in the stop position until relay P^a becomes energized, and this, of course, does not occur until the entire train passes out of block A-B. 110

Referring now to Fig. 2, in the modification here shown, the trackway circuit is connected with the track circuit directly instead of inductively as in Fig. 1. That is, the grid and filament of each amplifier are connected directly with the track rails at points 25 and 25^a which are a short distance from the low impedance bonds. In 115 this form of the invention the drop in potential along the track rails from point 25 through the bond to point 25^a is utilized to create an alternating difference of potential between the filament and the grid of the 120 amplifier. The result is the same as that secured with the apparatus shown in Fig. 1. Various other forms of apparatus may 125

be utilized to create a difference of potential in the grid circuit of each amplifier, due to the track circuit current.

Although I have herein shown and described only two forms of apparatus embodying my invention, it is understood that various changes and modifications may be made therein within the scope of the appended claims without departing from the 10 spirit and scope of my invention.

Having thus described my invention, what I claim is:

1. A railway signaling system for railways, the track rails of which are electrically 15 continuous throughout, comprising bonds of negligible impedance connected across the rails at intervals to form blocks, a source of alternating signaling current connected across the rails at substantially the middle 20 of each block and forming a closed track circuit with the bond at each end of the block, a fixed coil in inductive relation to a portion of each track circuit, a relay for each coil and located in the trackway, an electron 25 amplifier interposed between each coil and the corresponding relay, and roadside signals controlled by said relays.

2. A signaling system for railways for which the propulsion energy is direct current, comprising track rails, a track circuit including said rails and a source of alternating current; an electron amplifier located in the trackway and having a heated filament, a plate, and a grid interposed between the two; 30 a trackway circuit receiving a minute amount of energy from said track circuit and connected with the filament and grid of said amplifier, a plate circuit for said amplifier connected with the trolley wire and 35 with ground and including a relay, and a roadside signal controlled by said relay.

3. In combination, a railway, the propulsion energy for which is direct current, an alternating current transmission line extending 45 along said railway, a track circuit supplied from said transmission line and including the track rails of said railway; an electron amplifier located in the trackway and having a filament, a grid and a plate; a 50 trackway circuit receiving a minute amount of energy from said track circuit and connected with said filament and grid, means for supplying current to said filament from said transmission line, a plate circuit for 55 said amplifier connected with the trolley wire and with ground and including a relay, and a roadside signal controlled by said relay.

4. In combination, a railway track, an alternating current transmission line extending 60 along said track, a track circuit supplied from said transmission line and including the track rails of the railway, a trackway circuit receiving a minute amount of energy

from said track circuit; an electron amplifier located in the trackway and having a filament, a grid, and a plate; the terminals of said trackway circuit being connected with said filament and grid, means for supplying current to said filament from said 65 transmission line, a plate circuit for said amplifier including a source of direct current and a relay, and a roadside signal controlled by said relay.

5. In combination, a railway, the propulsion energy for which is direct current, an alternating current transmission line extending along said railway, a track circuit supplied from said transmission line and including the track rails of said railway; an electron amplifier located in the trackway and having a filament, a grid and a plate; a trackway circuit receiving a minute amount of energy from said track circuit and connected with the filament and grid of said amplifier, a transformer whose primary is connected with said transmission line and whose secondary is connected with the filament of said amplifier; a plate circuit for said amplifier comprising a connection from a trolley wire to the plate, and a connection from the middle point of the secondary of said transformer to ground; a relay included in said plate circuit, and a roadside signal controlled by said relay. 95

6. In combination, a railway track, an alternating current transmission line extending along said track, a track circuit supplied from said transmission line and including the track rails of said railway; an electron 100 amplifier located in the trackway and having a filament, a grid, and a plate; a transformer whose primary is connected with said transmission line and whose secondary is connected with the filament of said amplifier, a trackway circuit receiving a minute amount of energy from said track circuit and having its terminals connected with the grid of said amplifier and with the middle point of the secondary of said transformer, a plate circuit for said amplifier including a source of direct current and a relay, and a roadside signal controlled by said relay. 110

7. In combination, a railway, the propulsion energy for which is direct current, an alternating current transmission line extending along said railway, a track circuit supplied from said transmission line and including the track rails of the railway; an electron amplifier located in the trackway 115 and having a filament, a grid, and a plate; a transformer whose primary is connected with said transmission line and whose secondary is connected with the filament of said amplifier, a trackway circuit receiving a minute amount of energy from said track circuit and having its terminals connected respectively with the grid of said amplifier 120 125

and with the middle point of the secondary of said transformer; a plate circuit for said amplifier comprising a connection from the plate to the trolley wire, and a connection from the middle point of the secondary of said transformer to ground; said plate circuit including a relay, and a roadside signal controlled by said relay.

8. A railway signaling system comprising track rails, a track circuit comprising said rails and a source of alternating current, a trackway circuit receiving a minute amount of energy from said track circuit, a relay lo-

cated in the trackway and comprising two windings one of which is constantly energized from said source of alternating current, amplifying means interposed between said trackway circuit and the other winding of said relay, and a roadside signal controlled by said relay.

In testimony whereof I affix my signature in presence of two witnesses.
